AUTOMATIC TOOL

Walter Blair, Detroit, Mich., assignor of one-fourth to Charles L. Brown, Detroit, Mich.

Application August 7, 1939, Serial No. 288,817

9 Claims. (Cl. 81—125)

This invention relates, in general, to tools and, in particular, to a new and improved tool of the portable, automatic type.

One of the objects of this invention is to provide a new and improved tool device of the portable type which is easier to handle than formerly because of its simplified construction and more efficient in operation because of the new and improved arrangement of its parts.

Another object is to provide a tool device with a new and improved, automatically operable construction whereby the attachment means handled by the tool are so handled more efficiently and with better success than heretofore.

Another object is to provide a new and improved mechanism for a portable tool device whereby the rate of output is substantially unlimited because it is solely and automatically dependent upon the speed with which the operator manipulates the device.

Another object is to provide a new and improved tool device which is operable automatically and faultlessly for longer periods of time than heretofore.

Another object is to obviate, in a portable, automatic tool device, the faults and troubles heretofore found in and with devices of a similar character.

Other objects and advantages of the invention will become readily apparent from a reference to the following specification taken in conjunction with the accompanying drawings of which there are three (3) sheets and wherein:

Fig. 1 is a longitudinal, vertical view, partly in section and partly in elevation, of the tool;

Figs. 2 and 3 are views looking at the working end and in plan, respectively, of the showing in Fig. 1;

Figs. 4 and 6 are sectional views taken along the lines 4—4 and 6—6, respectively, in Fig. 1;

Fig. 5 is a view similar to Fig. 2 but looking at the opposite end of the tool;

Fig. 7 is a view similar to Fig. 1 but showing a different use for the tool and, as a result, a slightly modified construction thereof;

Figs. 8 and 9 are sectional views taken along the lines 8—8 and 9—9, respectively, in Fig. 7; and

Fig. 10 is an elevational view of a modified form of either of the tools shown in Figs. 1 and 7.

The tool shown in either of the Figs. 1 or 7 includes a main supporting body consisting of a head casing section 10 and a rear casing section 12, the section 10 serving, in general, to support a barrel 14 in which nuts 16 (see Fig. 1) or cap screws 18 (see Fig. 7) are housed or stored immediately prior to their attachment to the work and a clutch mechanism, generally indicated at 20, for selectively driving said barrel, the section 12 serving, in general, to support

the manually operable end 22 of a prime mover 24 for driving said clutch mechanism, and both of said sections 10 and 12 cooperating to support said prime mover and a multiple-chamber magazine, generally indicated at 26, for charging said barrel with said nuts or screws.

The head and rear casing sections 10 and 12 of the main supporting body in either Fig. 1 or 7, in assembly, are spaced from each other for accommodating therebetween the magazine 26, this spacing resulting from the disposal and connection of the front end of the casing of the prime mover 24 between and to supports 27 and 28 carried by or formed integrally with the rear end of said section 10 and from the attachment of the rear end of said prime mover casing to a support 29 carried by or formed integrally with the rear face of said section 12. The casing sections 10 and 12 and the prime mover 24 constitute, therefore, a rigid though separable unit, and it will subsequently be seen that the magazine 26 is freely supported by said unit for selective, rotary and lateral movements relatively thereto.

The head casing section 10 of the main supporting body shown in each of the Figs. 1 and 7 defines an open-ended chamber 30 in the ends of which is rotatably supported, such as by bearings 31, the barrel 14, said chamber also supporting, laterally of said barrel and by means of the front and rear walls of said casing section, the clutch mechanism 20. The rear end of the barrel 14 extends substantially to the plane of the rear face of the casing section 10, whereas the front end of said barrel extends outwardly from the plane of the front face of said section, and said barrel is prevented from axial movement relatively to said section, such as by properly arranged thrust nuts 32 screwed into said section about the open ends of the chamber 30, as shown in Figs. 1 and 7.

The power for rotating the barrel 14 originates at the prime mover 24 which is selectively operable by means of an ordinary switch lever 34 operatively connected to the energy source for said prime mover and located, for obvious reasons and as usual, in a handle member 35 therefor. This power is transmitted through the drive shaft of the prime mover 24 to a pinion 36 mounted thereon, thence from said pinion to the constantly rotatable member 37 of a slip clutch 38 of conventional design and mounted on a shaft 39 carried by and between the front and rear walls of the casing section 10 and finally from a pinion 40 carried on said shaft 39 to a gear 41 fixed on and for rotation with the barrel 14. The member or gear 37 of the slip clutch 38 is driven by and with the pinion 36; it is freely mounted about the shaft 39 but is prevented from axial movement therealong; and, it

comprises the driving member of said clutch. The driven member of the slip clutch 38 is in ratcheted, driven engagement with the driving member 37 thereof; it is mounted on the shaft 39 for rotation therewith and is capable of axial movement therealong; and, it is resiliently maintained in said driven engagement with said driving member by means of a spring 42 telescopically arranged on said shaft between said driven member and the pinion 40, the latter being fixedly carried on and rotated by said shaft. The purpose of the slip clutch is, of course, to enable slippage between its driving and driven members when the torque to which the barrel 14 is subjected becomes excessive or abnormal.

The casing sections 10 and 12 of the main supporting body shown in either of the Figs. 1 or 7 have formed integrally therewith upstanding plates 44 and 46, respectively, said plate 44 extending laterally from said section 10 at the plane of the rear end of the barrel 14 and said plate 46 extending in parallelism with said plate 44 and laterally from the supporting portion 29 of said section 12 for the prime mover 24 so as to provide a space therebetween for accommodation of the magazine 26. Each of the plates 44 and 46 is disc-shaped so as to confine therebetween the magazine 26 and cover the ends thereof, and each is provided with a radial slot 48 of predetermined depth so as to cooperate with each other to provide bearings for the removable and rotatable support of said magazine.

The magazine 26 is preferably an integral unit consisting of a pair of disc-shaped end plates 50 and 52 which are spaced from each other in parallelism and at a distance slightly less than the distance between the plates 44 and 46 by means of a series of tubular members 54 the axes of which are equally spaced from and parallel to each other and equally spaced from and parallel to the central axis of said magazine proper. The tubular members 54 are arranged so that their axes lie radially within the peripheries of the plates 50 and 52, and said members are longitudinally slotted, as at 55, to cooperate at one end of the magazine 26 with peripheral, circular openings 56 formed in said plate 52 and at the opposite end of said magazine with slots 57 formed in a rearwardly extending, cylindrical, flanged portion 58 of said plate 50 and with peripheral, circular openings 59 formed in said plate 50. In other words, the magazine 26 is comprised of a series of parallel, equi-annularly spaced, open-ended bores or storage chambers (formed by the members 54 and the openings 56 and 59) which extend from one end of said magazine to the other and which bores have access thereto along their entire lengths (by means of the slots 55 and 57 and the breaks in the peripheries of the plates 52 and 50 leading to the openings 56 and 59, respectively). These bores or chambers are preferably cylindrical in cross section (for reasons which will presently appear) and provide storage spaces for the nuts 16, in the one case, or for the cap screws 18, in the other case, their diameters being preferably, as shown, substantially similar to the greatest cross sectional dimension of either said nuts or the heads of said screws so that said nuts or said screws may be held, without inter-jamming, in substantial co-alignment therewithin.

The end plates 50 and 52 of the magazine unit 26 are provided at their centers with stub shafts or pins 60 which extend axially outwardly from said plates and cooperate with the slots 48 in

the plates 44 and 46 for being supported by the bases thereof. It will be noted that these bases of the slots 48 are at a common level which is parallel with the axis of the barrel 14 and which enables the magazine unit to be supported so that, during selective rotation of said unit, its bores or chambers will arrive consecutively into coaxial alignment with said barrel axis. As a precaution against inadvertent disarrangement of the shafts or pins 60 of the magazine unit 26 from the bases of the slots 48 in the plates 44 and 46, it has been found desirable to provide means, such as springs 61 and 62, for holding said unit in place with respect to said bases of said slots, spring 61 being anchored at one of its ends to the casing section 10 and resiliently abutting at its free end the front, upper portion of the adjacent pin 60, and spring 62 being anchored at one of its ends to the casing section 12 and resiliently abutting at its free end the rear, upper portion of the other and adjacent pin 60. With this arrangement it is clear that the magazine unit 26 is free to rotate about its axis as well as to be readily assembled to and disassembled from the sections 10 and 12 of the main body support therefor.

Each of the tubes 54 of the magazine unit 26 in either of the Figs. 1 or 7 is formed, at its forward end and diametrically opposite its slot 55, with a comparatively short, longitudinally directed slot 64 and, at its rearward end, with another and similar slot 65. To the wall of each tube 54 adjacent the rearward end of the slot 64 there is anchored an end of a leaf spring 66 which extends forwardly to substantially the forward face of the plate 50 and resides normally within said slot to provide therealong a flexible and substantial continuity in the inner surface of said tube. To the wall of each tube 54 adjacent the forward end of the slot 65 there is secured an end of a stop member 67 which extends rearwardly to a position slightly spaced from the forward face of the plate 52 and resides within said slot and also within the bore formed by said tube, it perhaps being preferable, though optional, to carry said stop member resiliently within said bore rather than rigidly, and this provision is shown. Prior to positioning the magazine unit 26 between the plates 44 and 46, the bores or chambers formed by the tubes 54 of said unit are filled from their forward ends with the nuts 16 or screws 18, not necessarily as uniformly as shown but at least on their sides so as to enable their coaxial alignment while therewithin, and the stop members 67 serve to limit the numbers thereof so that the forward ends of the forwardmost nuts or screws will extend, when said unit is in assembly with said plates, into substantially flush engagement with the rear face of the casing section 10 with which the rear end of the barrel 14 is also flush. As will be seen, the function of each of the springs 66 comes into play when its respective tube 54 of the magazine 26 arrives into alignment with the barrel 14, this function being to prevent rotation of the forwardmost nut or screw in said tube and held by said spring from rotating or being caused to rotate by its contact with the rearwardmost nut or screw in the rotating barrel, thereby facilitating the introduction of the non-rotating nut or screw into said rotating barrel from said magazine tube. This feature is important in that the internal cross section of the barrel 14 is polygonal, as at 68, so as to receive and rotatably drive the nuts 16 or screws 18.

therein, and for this reason there should be provided a relative rotation between the rearwardmost nut or screw in said barrel and the forwardmost nut or screw in the magazine chamber 54 then in alignment with said barrel; this relative rotation will present a moment at which the cross sections of the barrel bore and the nut or screw head in the magazine chamber will be exactly complementary and whereupon forward pressure upon the nut or screw in said chamber will positively drive said nut or screw into proper position within said bore.

The means for displacing the nuts 16 or screws 18 from that magazine chamber 54 which is in alignment with the barrel bore 68 into said bore comprises an ejector element 70 which is in the form of an upstanding lug having tapered sides (see Fig. 6) substantially complementary to the tapered side walls of the slots 55 and 57. The element 70 is held in projected position within that slot 55 of the tubular element 54 which is in alignment with the barrel 14 by means of a leaf spring 71, said ejector being connected to the free end of said spring and the other end of said spring being anchored to a block 72 reciprocally carried on an elongated, stationary guide rod 73 therefor carried at one end by the supporting portion 28 of the casing section 10 and at its other end by the rear end of the handle portion 35 of the casing section 12. Telescopically mounted about the guide rod 73 between the block 72 and the wall of the handle portion 35, preferably within a bore 74 therefor, is a coil spring 75 which urges said block and the element 70 carried thereby forwardly and exerts a pressure, through said block, upon the row of nuts 16 or screws 18 in the chamber 54 thereadjacent, said block normally abutting the rearwardmost nut or screw in said chamber. It will be seen in Fig. 1 or 7 that the magazine chamber 54 which is in alignment with the barrel 14 is full of the attachment means 16 or 18 and that the ejector element 70 is in its rearwardmost position in opposition to the spring 75, this being the beginning of the stroke of said element for the discharging of said means from said chamber into said barrel. The following forward movement of the ejector 70 is caused by the actions of the spring 75 and of means (to be described) carried by the head end of the barrel 14, and during this movement, which is guided by the guide rod 73, the magazine is held non-rotatably by means of the engagement between said ejector and the slot 55 and the preferable provision of the polygonal cross section of said rod. The end of the discharge stroke of the element 70 occurs while said element is in the slot 57 of the flange 58 and when the last nut 16 or screw 18 has been driven into the barrel bore 68 from the magazine chamber 54 in alignment therewith. Thereupon, the magazine 16 is revolved manually until the next chamber 54 is aligned with the barrel 14, this action being possible because of the tapered side walls of the element 70 and slots 57 and/or 55 and the resiliency of the spring 71, and the block 72 is then drawn bodily rearwardly, by means such as a handle 16 secured thereto, with said element residing in the new slot 55 and being pulled therealong over the nuts 16 or screws 18 thereabove, until said element becomes positioned behind the new and rearwardmost nut or screw. The action is then repeated.

The description so far outlined is applicable to either the device shown in Fig. 1 or to that

shown in Fig. 7, but, in view of the fact that one is employed in conjunction with the nuts 16 and the other with the cap screws or bolts 18, there is a slight difference in the head end constructions of the two devices, and these constructions and their differences will now be outlined.

To the threaded, forward end of the rotatable barrel 14 in Fig. 1 there is removably secured for rotation therewith a forwardly extending head member 78 having a longitudinal bore 79 in alignment and continuity with the bore 68 so that a nut 16 in said bore 68 encounters no difficulty in passing into said bore 79. The wall of the head member 78 is formed therethrough at its forward end with a pair of diametrically opposite, longitudinally extending slots 80 between the opposite side walls of each of which slots there is pivotally carried, by means of a pin 81 secured to said side walls, a pawl or catch 82. The pawls or catches 82 are so pivoted intermediate their ends by the pins 81 as to oscillate within the slots 80 relatively to the head member 78, the forward end of each pawl or catch having a portion 83 residing normally within the bore 79 in direct abutment with the forward peripheral edge of the forwardmost nut 16 in said bore 79, and the rearward end of each pawl or catch having an anchored thereto the rear end of a forwardly extending spring catch 84 which has a front portion 85 residing normally within its respective slot 80 and said bore 79 between the first and second nuts 16 in said bore and in direct abutment with the forward peripheral edge of said second nut. The force exerted by the spring 75 through the ejector element 70 upon the nuts 16 in the bores 54, 68 and 79 is insufficient to move the first nut 16 in the row past the portions 83 of the pawls 82-83, but it is sufficient to move the whole row of nuts forwardly in the event the portions 85 of the catches 84-85 are residing substantially externally of the bore 79 and the first nut has been discharged from said bore. Therefore, when the device shown in Fig. 1 has been positioned adjacent the work with the first nut 16 in the bore 79 properly initiated into its attachment thereto, and the unitary rotation of the barrel 14 and head member 78 is begun, completing the attachment of said nut to said work will draw said nut past the pawls 82-83, thereby moving the forward portions 83 of said pawls outwardly of said bore, and the rearward ends thereof in the direction of said bore. This inward movement of the rear ends of the pawls 82-83 causes the forward portions 85 of the catches 84-85 to move toward each other and positively clamp the next nut 16 in line from moving therewith under the force of the spring 75. However, this concerted action of the pawls 82-83 and catches 84-85 endures only until the first nut 16 has passed the forward portions 83 of said pawls because said action is in opposition to the spring forces of said catches. So, when the first nut 16 has passed the portions 83 of the pawls 82-83, said portions immediately move into or even inwardly of their normal positions within the bore 79, thereby reducing the holding force of the catches 84-85 on the nut next in line and throwing the portions 85 of said catches substantially outwardly of said bore, the spring 75 then being effective to advance the row of nuts in the bores 54, 68 and 79 so as to move said next nut past said portions 85 into position against said portions 83 of said pawls 82-83. Immediately upon the engagement of the head nut 16 with the pawl portions 83, the pawls

82—83 and catches 84—85 re-assume their positions as shown in Fig. 1. When the nut 16 is being attached to the work, it is only natural for the operator to apply a push on the forward end of the device, and this push would tend to move the nuts in the bores 79, 68 and 54 backwardly if it were not for the opposition thereto of the retarding effect caused by the portions 25 of the catches 84—85 and the spring 75.

On the other hand, to the forward, threaded end of the barrel 14 of the device shown in Fig. 7 there is removably connected a head member 178 having, like the member 78, a bore 79 of polygonal cross section and in alignment and continuity with the bore 68 so that a screw 18 can pass from the latter to the former with no difficulty. The member 178, instead of having the slots 80, is formed with two pairs of axially spaced apertures 86 and 87, the forward apertures 86 being coaxially aligned and reciprocably receiving in each a plunger 88, and the rearward apertures 87 being coaxially aligned and reciprocably receiving in each a plunger 89. The plungers 88 at their inner ends are tapered in a forward direction and reside normally in immediate contact with the forward peripheral edge of the head of the forwardmost screw 18 in the bore 79, and in resilient, guiding contact with the stem of said screw by means of a pair of leaf springs 90 which engage at their free ends said plungers and are anchored at their other ends to the member 178. The plungers 89 are also tapered at their inner ends in a forward direction and reside immediately behind the head of the forwardmost screw 18 in the bore 79 to prevent rearward displacement of said screw during its attachment to the work, said plungers being resiliently held in place by means of leaf springs 91 contacting at their forward ends said plungers and being anchored at their rearward ends to the member 178. When the forwardmost screw 18 in the bore 79 is introduced to the work, the resulting pull thereon will cause it to pass beyond the spring impressed plungers or stops 88, and the force of the spring 75 will simultaneously move the next screw in line past the lightly held plungers or stops 89 into the position formerly occupied by the first screw, that is, with its head up against the relatively stronger held plungers or stops 88. The normal positions of the plungers or stops 88 and 89 are shown in Fig. 7 and are made possible by means of shoulders 92 and 93 formed thereon and cooperable with the member 178 to limit the inward movements thereof to said positions.

It will be noted in both of the Figs. 1 and 7 that the head members 78 and 178 extend forwardly beyond their particular means (82—83 in Fig. 1 and 88 in Fig. 7) for holding the forwardmost nut and screw in the bores therefor in said head members, and the reason for this is to enable an abutment between said head members and the work and thereby effectuate a positive outward movement of said nut and screw relatively to the device to operate said means 82—83 and 88 in the previously outlined manners.

The modified form of device shown in Fig. 10 is similar in detail, operation and construction to that of the device shown in Fig. 1 or to that of the device shown in Fig. 7, except that the magazine 26 has been eliminated and replaced by a tube 154 having the fundamental and necessary characteristics of any of the tubes 54 and the casing section 12 has been substituted by the casing section 112 for supporting said tube in

such a way that the latter is arranged at its forward end in adjacency to the barrel bore 68 and with its rearward end leading to a hopper (not shown) or other storage chamber for the attachment means 16 or 18. The discharge of the attachment means 16 or 18 from the tube 154 into the barrel bore 68 and thence to the work has previously been described and is not needful of being repeated.

10 Although the invention has been described with some detail it is not intended that such detailed description is to be definitive of the limits of the inventive idea. The right is reserved to make such changes in the details of construction and arrangement of parts as will fall within the purview of the attached claims.

What I claim is:

1. In a tool device, a rotatable holder having a longitudinal bore of polygonal cross section with a series of like-shaped, aligned attachment members residing therewithin, said bore being open at both of its ends, a non-rotatable holder arranged immediately adjacent said first holder and having a longitudinal bore of substantially circular cross section in alignment with said first bore with another series of aligned attachment members residing therewithin and forming with the first attachment members an unbroken row thereof, said second bore being open at the end thereof adjacent said first bore, means for urging the displacement of the attachment members in said second bore therefrom into said first bore, and means cooperable with the attachment member in said second bore most adjacent said first holder for reducing the tendency caused by its contact with the attachment member in said first bore most adjacent said second holder to rotate.

2. In a tool device, a rotatable holder having a longitudinal bore of polygonal cross section with a series of like-shaped, aligned attachment members residing therewithin, said bore being open at both of its ends, a non-rotatable holder arranged immediately adjacent said first holder and having a longitudinal bore of substantially circular cross section in alignment with said first bore with another series of aligned attachment members residing therewithin and forming with the first attachment members an unbroken row thereof, said second bore being open at the end thereof adjacent said first bore and provided at its opposite end with a removable restriction, means for urging the displacement of the attachment members in said row toward the open outer end of said first bore, and means carried by one of said holders and cooperable with the attachment member in said second bore most adjacent said first holder for reducing the tendency caused by its contact with the attachment member in said first bore most adjacent said second holder to rotate.

3. In a tool device having a rotatable barrel of internal, polygonal cross section and from which attachment members are individually ejected for attachment to workpieces and a force applicator movable toward the barrel for effectuating such ejection, a magazine for storing the attachment members prior to their introduction to the barrel and comprising, a plurality of open-ended, elongated holders of internal, cylindrical cross section for the attachment members arranged in parallelism with the barrel and in equally spaced relationship about a central axis of rotation, said magazine being supported at said axis of rotation and movable thereabout for suc-

cessively aligning the open ends of said holders with the barrel, longitudinal openings in the walls of said holders for individually receiving the applicator and guiding same during its movement therealong, and springs carried by said holders at their open ends and resiliently engageable with the forwardmost members therein.

4. In a tool device, a barrel having a longitudinal bore with a series of attachment members residing in co-alignment therewithin and movable therealong, said bore having an outlet at one of its ends for the members, means for exerting a force upon the members to protract the latter in the direction of said outlet, pawl means supported for movement about an axis between a pair of positions therefor at one of which said pawl means resides in the path of protraction of the foremost member in said bore to oppose said protraction and at the other of which said pawl means resides in lateral spaced relation to said path responsive to attachment of said foremost member to a work piece therefor, and second pawl means resiliently carried by said first pawl means for movement substantially unitarily therewith about said axis and extensible into position ahead of the member next in line to said foremost member for normally urging said first pawl means into said first mentioned position therefor and opposing protraction of said next-in-line member.

5. In a tool device, a rotatable holder having a longitudinal bore of polygonal cross section with a series of like-shaped, aligned attachment members residing therewithin, said bore being open at both of its ends, a non-rotatable holder arranged immediately adjacent said first holder and having a longitudinal bore of substantially circular cross section in alignment with said first bore with another series of aligned attachment members residing therewithin and forming with the first attachment members an unbroken row thereof, said second bore being open at the end thereof adjacent said first bore, stop means for said row in said second bore at the end of the latter most remote from said first bore, means for urging the displacement of the attachment members in said second bore therefrom into said first bore, and means cooperable with the attachment member in said second bore most adjacent said first holder for reducing the tendency caused by its contact with the attachment member in said first bore most adjacent said second holder to rotate.

6. In a tool device having a rotatable barrel of internal, polygonal cross section and from which attachment members are individually ejected for attachment to work pieces and a force applicator movable toward the barrel for effectuating such ejection, a magazine for storing the attachment members prior to their introduction to the barrel and comprising, a plurality of open-ended, elongated holders of internal, cylindrical cross section for the attachment members arranged in parallelism with the barrel and in equally spaced relationship about a central axis of rotation, said magazine being supported at said axis of rotation and movable thereabout for successively aligning the open ends of said holders with the barrel, longitudinal openings in the walls of said holders for individually receiving the applicator and guiding same during its movement therealong, spring impressed stops cooperable with the ends of said holders opposite

their open ends, and springs carried by said holders at their open ends and resiliently engageable with the forwardmost members therein.

7. In a tool device having a rotatable barrel of internal, polygonal cross section and from which attachment members are individually ejected for attachment to work pieces and a force applicator movable toward the barrel for effectuating such ejection, a magazine for storing the attachment members prior to their introduction to the barrel and comprising, a plurality of open-ended, elongated holders of internal, cylindrical cross section for the attachment members arranged in parallelism with the barrel and in equally spaced relationship about a central axis of rotation, said magazine being supported at said axis of rotation and movable thereabout for successively aligning the open ends of said holders with the barrel, means for opposing said rotation of said magazine, longitudinal openings in the walls of said holders for individually receiving the applicator and guiding same during its movement therealong, and springs carried by said holders at their open ends and resiliently engageable with the forwardmost members therein.

8. In a tool device having a rotatable barrel of internal, polygonal cross section and from which attachment members are individually ejected for attachment to work pieces and a force applicator movable toward the barrel for effectuating such ejection, a magazine for storing the attachment members prior to their introduction to the barrel and comprising, a plurality of open-ended, elongated holders of internal, cylindrical cross section for the attachment members arranged in parallelism with the barrel and in equally spaced relationship about a central axis of rotation, said magazine being supported at said axis of rotation and movable thereabout for successively aligning the open ends of said holders with the barrel, means for opposing said rotation of said magazine, longitudinal openings in the walls of said holders for individually receiving the applicator and guiding same during its movement therealong, spring impressed stops extending normally into said holders at the ends of the latter opposite the open ends thereof, and springs carried by said holders at their open ends and resiliently engageable with the forwardmost members therein.

9. In a tool device, a rotatable holder having a longitudinal bore of polygonal cross section with a series of like-shaped, aligned attachment members residing therewithin, said bore being open at both of its ends, a non-rotatable holder arranged immediately adjacent said first holder and having a longitudinal bore of substantially circular cross section in alignment with said first bore with another series of aligned attachment members residing therewithin and forming with the first attachment members an unbroken row thereof, said second bore being open at the end thereof adjacent said first bore, means for urging the movement of the attachment members in said row toward the outer open end of said first bore, and spring means resiliently cooperable with the attachment member in said second bore most adjacent said first holder for reducing the tendency caused by its contact with the attachment member in said first bore most adjacent said second holder to rotate.

WALTER BLAIR.
